UNITED STATES PATENT OFFICE.

HARRY C. CROZIER, OF PHOENIX, ARIZONA.

LOOSE-LEAF BINDER.

1,072,919.

Specification of Letters Patent.

Patented Sept. 9, 1913.

Application filed October 25, 1912. Serial No. 727,812.

To all whom it may concern:

Be it known that I, HARRY C. CROZIER, a citizen of the United States, residing at Phoenix, in the county of Maricopa and State of Arizona, have invented new and useful Improvements in Loose-Leaf Binders, of which the following is a specification.

The present invention has reference to loose-leaf binders, and it comprehends, briefly, certain hereinafter described improved devices for holding the leaves or pages in separate groups within the book, and devices detachably associated with the aforesaid holders for supporting and maintaining the same in position, and for causing the covers and the groups of leaves to assume approximately flat positions when the book is opened.

The invention further resides in the provision of improved expanding or contracting devices to increase or decrease the holding capacity of the book.

An embodiment of the invention is illustrated in the accompanying drawing, whereof:

Figure 1 is a plan view of the improved binder in open position, with parts in section and broken away; Figs. 2 and 3 are enlarged fragmental transverse sections taken, respectively, on the lines 2-2 and 3-3 of Fig. 1, and showing the binder substantially closed; Fig. 4 is an enlarged section taken longitudinally of one of the covers on the line 4-4 of Fig. 1; Figs. 5 to 8 are juxtapositional perspective views of the component parts of one of the holders and a leaf about to be inserted thereinto; Fig. 9 is an enlarged transverse section showing the manner in which the holder is connected to the afore-mentioned supporting device; Fig. 10 is a view similar to Fig. 9, but showing a slightly modified form of holder; Figs. 11 and 12 are, respectively, a plan view and an enlarged fragmental transverse section of a modified form of binder.

Referring to said drawings, and more especially to Figs. 1, 2 and 3, wherein the preferred form of the invention is depicted, A, A indicate, generally, the two covers, and B the back of the binder, the parts A, A being, in the main, of conventional type. The two covers and the back are hingedly connected together, to permit the requisite movements of the first-mentioned parts, such connections being of either indirect or direct character according as expanding or con-

tracting mechanism is provided or omitted. In the latter construction, depicted in Figs. 11 and 12, the covers A', A' have their inner edges hinged directly to the adjacent edges 60 of the back B', as indicated by the numeral 9'. The preferred construction, illustrated in the first-mentioned figures, includes the expanding or contracting mechanism above referred to, and this mechanism, which is 65 indicated in a general manner by the character D, may advantageously consist of the following instrumentalities: a vertical rod 5, arranged longitudinally and centrally of the back B, and journaled in suitable bearings 6 70 provided upon said back; a pair of transversely-curved or bowed metal plates 7, disposed against the inner face of back B; and a series of devices 8 actuated by said rod, upon rotation thereof, to force the said 75 plates toward or from each other. These plates have a hinge connection 9 at their outer edges with the adjacent covers, and their inner edges are disposed in spaced parallel relation, their upper and lower ends 80 being slidably fitted in guides 10 produced by bending inwardly the ends of the back. The plate-shifting devices 8 are here shown as comprising, each, upper and lower pairs 85 of toggle arms 11 and 12 whose mutually-adjacent outer ends are pivotally connected together by means of studs 13 fixed to said plates, and whose inner ends are pivoted to collars 14 and 15 slidable upon the reversely-threaded portions 16 and 17 of the rod. To 90 effect the rotation of said rod, one of its ends is squared, as indicated by the numeral 18, for engagement by the shank of a suitable key 19 indicated in dotted lines in Fig. 1, the rotary movement imparted to the rod in 95 the obvious manner by means of this key serving to move the collars toward or from each other and thus expand or contract the toggles, with the result that the requisite movements of the plates and covers are obtained. In both forms of the invention, the covers are directly connected by means of suitable devices 20 which are detachably associated therewith and with the hereinafter-described holders, and serve to hold the 100 covers and the groups of leaves carried by the holders in approximately flat positions when the book is opened. These devices are preferably in the form of spring metal strips which extend transversely across the back B 110 and have their ends removably inserted in metal sheaths or cases 21 fastened or embed-

ded in place between the plies or laminae of the covers, as represented in Figs. 1, 2, 4 and 12; they may have any tension or bearing force that may be considered advisable. In explanation of the foregoing, it may be stated that when the book is open, the springs occupy the position represented in Fig. 12, which may be regarded as their normal position, and consequently, the tension or bearing force exerted by their ends upon the covers and the groups of leaves tends to hold the same in such position. The leaves or pages of the book are arranged in individual groups each of which is carried by a holder; these holders embodying the most important features of the invention. They are supported and maintained in position by means of the above-described spring strips 20. In their preferred form, the holders E embody, each, the several parts or elements depicted in Figs. 5, 6 and 7 and comprising a body member 22, adapted to receive the inner edges of a group of leaves 23, an attaching member 24 hinged to the body member and adapted for direct connection to the strips 20, and a rod-like locking member 25 directly associated with the attaching member 24. The receiving or body member 22 has, by preference, the form of a narrow, elongated trough-like case, which is closed at its ends and open along its front; at its back, it is provided with a series of knuckles 26 that are spaced from each other to receive therebetween the complementary knuckles 27 provided upon the adjacent longitudinal edge of the attaching member 24, which latter has a U-shaped or trough-shaped formation and is open at its ends to receive the sliding locking member 25. The sets of knuckles 26 and 27 receive the pintle 28 of the hinge joint, whereby the body member may be swung or turned upon said pintle in the ordinary manner, to permit the group of leaves carried by the holder to assume a flat position, as depicted in Fig. 9. The strips 20 pass through registering slots 28 and 29, in the attaching and locking members 24 and 25, respectively, the latter slots having an L-shaped formation so as to produce elongated locking fingers 30. The locking member, when inserted into the attaching member, is adapted, therefore, to be moved endwise in an inward direction until its fingers project across the slots 28, thus closing the same and retaining the supporting strips 20 in place. When the locking member is moved in the opposite direction, the aforesaid fingers will be withdrawn into inoperative position, as will be understood, thereby opening the slots 28 and permitting the holder to be detached from strips 20. To facilitate its operation, the said locking member is furnished at one end with a suitable finger-piece or handle 31. In order to permit the insertion of the binding

edges of the leaves or pages 23 into the body member 22 and their subsequent retention in place therein, the aforesaid member is preferably constructed of two separate parts or sections 22^a and 22^b, which are designed for relative movement, and the knuckles 26 on this member are formed alternately, first on one part or section, and then on the other part or section, as will be seen from inspection of Fig. 7. The inner section 22^b of the body member is provided with a series of studs 32, which are rigidly secured thereto and are provided with flat heads 32^a, and these studs are designed to project through wedge-shaped slots 33 formed in the outer section 22^a, and, also, through openings 34 in the binding edges of the leaves 23. The alternating knuckles on the two sections of the said body member are, of course, arranged in alignment to permit the pintle or hinge rod 28 to pass therethrough, and inasmuch as these knuckles are spaced a slight distance apart, it will be apparent that the section 22^a may be moved endwise in one direction, (toward the left in Fig. 7), relative to the other part or section 22^b, until the stud heads 32^a are opposite the enlarged portions of the slots 33. The section 22^a may then be swung away from the section 22^b upon the hinge rod as a pivot, after which the studs may be passed through the leaf openings 34. The section 22^a is next swung back upon the leaves, and the studs thus caused to project through the large portions of said slots, and, finally, said section is shifted endwise toward the right, to bring the stud heads into engagement with the narrow portions of the slots; thus locking the two sections together and the leaves in place therebetween. The section 22^a is preferably corrugated longitudinally, as indicated by the numeral 35 in Figs. 7 and 9, to prevent the stud heads from projecting beyond the plane of said section.

From the foregoing, it will be understood that the construction of the holder is such as to enable a group of leaves or pages to be readily and quickly inserted therein and fixed in place owing to the two-part formation of the body member and the ability of one of these parts or sections to move both pivotally and endwise relative to the other section; the body member itself to be swung in either direction relative to the attaching member, to permit it to lie approximately flat; and the holder, as a whole, to be readily and quickly attached to and detached from the supporting strips 20, owing to the provision of the sliding locking member.

While the preferred form of holder is that above described, a holder possessing substantially the same advantages and having the same main elements may be constructed as illustrated in Fig. 10. This holder, designated, generally, by the reference letter E',

has its body member 22' made in two parts or sections, and the outer section movable relatively to the inner section, as in the first construction, but the latter section is formed 5 integral with the corresponding wall of the attaching member 24' instead of being separate therefrom. Also, the knuckles 26' are formed only on the said outer section of the body member and the knuckles 27' on the 10 outer wall of the attaching member, so that the rod 28' serves only as the pivot upon which the outer section of the body member is swung during the fastening of the leaves in the holder. The locking member 25' is 15 substantially identical with the corresponding element in the preferred construction.

I claim as my invention:—

1. In a loose-leaf binder, the combination, with connected back and cover elements; of 20 a plurality of transversely-arranged spring metal strips connected at opposite ends to said covers for holding the same in substantially flat position when the binder is opened.

2. In a loose-leaf binder, the combination, 25 with connected back and cover elements; of a plurality of transversely-arranged spring metal strips detachably connected at opposite ends to said covers for holding the same in substantially flat position when the 30 binder is opened.

3. In a loose-leaf binder, the combination, with connected back and cover elements, each cover having a transversely-arranged sheath embedded in it; of a plurality of 35 spring metal strips having their opposite ends removably fitted in said sheaths, for holding said covers in substantially flat position when the binder is opened.

4. In a loose-leaf binder, the combination, 40 with connected back and cover elements; of a plurality of transversely-arranged spring metal strips connected at opposite ends to said covers for holding the same in substantially flat position when the binder is opened; and a plurality of holders detachably connected to said strips, each of said 45 holders being adapted to receive the binding edges of an individual group of leaves.

5. In a loose-leaf binder, the combination, 50 with the back and covers, and devices connecting said covers; of a series of holders each adapted to contain an individual group of leaves removably connected to said devices and comprising each, connected body 55 and attaching members and a locking member associated with the latter member.

6. In a loose-leaf binder, the combination, with the back and covers, and devices connecting said covers; of a series of holders 60 each adapted to contain an individual group of leaves removably connected to said devices and comprising, each, connected body and attaching members and a locking member slidably fitted in the latter member.

65 7. In a loose-leaf binder, the combination,

with the back and covers, and devices connecting said covers; of a series of holders each adapted to contain an individual group of leaves removably connected to said devices and comprising, each, connected body and attaching members and locking means associated with the second-named member, the first-named member consisting of a pair of separate sections one of which is movable relatively to the other. 70

8. In a loose-leaf binder, the combination, with the back and covers, and devices connecting said covers; of a series of holders each adapted to contain an individual group of leaves removably connected to said devices and comprising each connected body and attaching members and locking means associated with the second-named member, the first-named member consisting of a pair of separate sections one of which is movable 80 pivotally and endwise relatively to the other. 85

9. In a loose-leaf binder, the combination, with the back and covers, and devices connecting said covers; of a series of holders 90 each adapted to contain an individual group of leaves removably connected to said devices and comprising, each, hingedly-connected body and attaching members and locking means associated with the latter 95 member.

10. In a loose-leaf binder, the combination, with the back and covers, and devices connecting said covers; of a series of holders each adapted to contain an individual 100 group of leaves removably connected to said devices and comprising, each, hingedly-connected body and attaching members and a locking member slidably fitted in the latter member. 105

11. In a loose-leaf binder, the combination, with the back and covers, and devices connecting said covers; of a series of holders each adapted to contain an individual group of leaves removably connected to said devices and comprising, each, connected body and attaching members and locking means associated with the second-named member, the first-named member consisting of a section provided with headed leaf-fastening 110 studs and a second section movable endwise relatively to the first section and having wedge-shaped slots through which said studs project. 115

12. In a loose-leaf binder, the combination, with the back and covers, and devices connecting said covers; of a series of holders each adapted to contain an individual group of leaves removably connected to said devices and comprising, each, connected body 120 and attaching members and locking means associated with the second-named member, the first-named member consisting of a section provided with headed leaf-fastening 125 studs and a second section movable endwise through which said studs project. 130

and pivotally relatively to the first section and having wedge-shaped slots through which said studs project.

13. In a loose-leaf binder, the combination, with the back and covers, and devices connecting said covers; of a plurality of holders adapted to receive individual groups of leaves removably connected to said devices and comprising, each, connected body and attaching members, the latter of which is provided with slots for the reception of said devices, and a movable locking member associated with said attaching member and having means for closing said slots to retain said devices therein.

14. In a loose-leaf binder, the combination, with the back and covers, and devices connecting said covers; of a plurality of holders adapted to receive individual groups of leaves removably connected to said devices and comprising, each, connected body and attaching members, the latter of which is provided with slots for the reception of said devices, and a movable locking member associated with said attaching member and having retaining fingers adapted to be brought into and out of position to close said slots during the movements of the locking member.

15. In a loose-leaf binder, the combination, with the back and covers, and devices connecting said covers; of a plurality of holders adapted to receive individual groups of leaves removably connected to said devices and comprising, each, connected body and attaching members, the latter of which is provided with slots for the reception of said devices, and a locking member slidable endwise within said attaching member and having means for opening or closing said slots during its movements.

16. In a loose-leaf binder, the combination, with the back and covers, and devices connecting said covers; of a plurality of holders adapted to receive individual groups of leaves removably connected to said devices and comprising, each, connected body and attaching members, the latter of which is provided with slots for the reception of said devices, and a locking member slidable endwise within said attaching member and having longitudinal retaining fingers adapted to be brought into position to extend across said slots for closing the same.

17. In a loose-leaf binder, the combination, with the back and covers, and spring strips connected at opposite ends to said covers for holding the same approximately flat when the binder is opened; of a plurality of holders adapted each to receive an individual group of leaves removably connected to said strips.

18. In a loose-leaf binder, the combination, with the back and covers, and spring strips connected at opposite ends to said covers for holding the same approximately flat when the binder is opened; of a plurality of holders adapted each to receive an individual group of leaves embodying, each, connected body and attaching members, the latter of which is adapted for engagement with said strips, and means associated with said attaching member for releasably retaining the same in such engagement.

19. In a loose-leaf binder, the combination, with the back and covers, and spring strips connected at opposite ends to said covers for holding the same approximately flat when the binder is opened; of a plurality of holders adapted each to receive an individual group of leaves embodying, each, connected body and attaching members, the latter of which is adapted for engagement with said strips, and a slidable locking member associated with said attaching member for releasably retaining the same in such engagement.

20. In a loose-leaf binder, the combination, with the back and covers, and spring strips connected at opposite ends to said covers for holding the same approximately flat when the binder is opened; of a plurality of holders adapted each to receive an individual group of leaves embodying, each, hingedly-connected body and attaching members, the latter of which is adapted for engagement with said strips, and means associated with said attaching member for releasably retaining the same in such engagement.

In testimony whereof I have hereunto set my hand in presence of two subscribing witnesses.

HARRY C. CROZIER.
